ATTORNEYS,

UNITED STATES PATENT OFFICE.

JOHN B. HARRIS, OF EUTAW, ALABAMA.

WINDOW BURGLAR-GUARD.

SPECIFICATION forming part of Letters Patent No. 396,157, dated January 15, 1889.

Application filed November 20, 1888. Serial No. 291,386. (No model.)

To all whom it may concern:

Be it known that I, JOHN B. HARRIS, of Eutaw, in the county of Greene and State of Alabama, have invented a new and Improved 5 Window Burglar-Guard, of which the following is a full, clear, and exact description.

This invention has for its object to provide a device which will prevent a person from surreptitiously gaining access to a building 10 through a window, and by means of which a person attempting to unlawfully enter a building through a window will be caught and held a prisoner.

The invention consists in a device for the 15 above purpose constructed and arranged as hereinafter described and claimed.

Reference is to be had to the accompanying drawings, forming a part of this specification, in which similar figures of reference indicate 20 corresponding parts in all the figures.

Figure 1 is a view of a window from the inside with a portion broken away, showing the invention applied. Fig. 2 is a detail thereof at one side of the window, partly broken 25 away and in section, showing automatic catch for holding the guard in raised or set position and locking it after it is tripped. Fig. 3 is a detail, partly broken away and in section, looking at the side of the window and showing 30 means for automatically tripping and operating the guard; and Fig. 4 is a detail in horizontal section of a portion of the window-frame with adjacent portions of the invention.

35 In carrying out this invention I provide a window-frame, 1, with a vertically-sliding metallic grating, 2, serving as a window-guard and having the lower ends of its vertical bars 3 formed with sharp points 4. The grating 2 40 may be mounted in the window-frame 1, to slide vertically therein on the inside of window 5 in any suitable manner, and, as here shown, preferably by means of the following-described construction: The inner face of the 45 sides of the window-frame 1 is formed with semicircular groove 6, extending from top to bottom of the window-frame, and over the inner face of the sides of the window-frame is secured a strip of wood or molding, 7, having 50 a semicircular groove, 8, coinciding with and corresponding to the groove 6 and forming therewith a circular recess or pocket, 9.

Within the pockets 9 on the sides of the window-frame 1 are located vertical bars 10, mounted at their ends on the projecting ends 55 11 of the cross-bars 12 of grating 2 and at their middle on projections 13 on the sides of grating 2. The projecting ends 11 and the projections 13 extend through slots 14, running from top to bottom of the inside of pockets 9, and serving as guides for the grating in its vertical movement.

To hold the grating in raised position when it is set for use, a lever, 15, is provided, having a cam-shaped head, 16, pivoted in a recess, 17, in the side of window-frame 1 at some little distance above the window-sill, and a curved arm, 18, projecting out of the recess 17. The lever 15 has a pin, 19, projecting therefrom adjacent to its pivotal point, so 70 that when the arm 18 is elevated nearly to a vertical position the pin 19 will have been moved into one of a series of holes, 20, in the vertical bar 10, and will hold the grating 2 in raised position. To lock the grating 2 when 75 it is lowered, the cam-shaped head 16 is provided with teeth 21, which, when the arm 18 is lowered and the pin 19 withdrawn from a hole, 20, are moved into engagement with the serrated edge 22 on the right-hand bar 10, and 80 are locked therewith, as shown in Fig. 2.

At a suitable height on the side of window-frame 11 is mounted a bracket, 23, in the shape of a ring, and hinged to the outer portion of the bracket 23 is a ring, 24, fitting over 85 the ring 23 and having an arm, 25. Upon the ring 24 rests a weighted ball, 26, having secured thereto one end of a cord, 27, leading to and secured at its other end to the arm 18 of lever 15. A cord, 28, is fastened at one 90 end to arm 25 and leads therefrom across the lower portion of window 5 to the opposite side of window-frame 1, where it is secured to a staple, 29. Beneath the window-frame 1 is located a board, 30, serving as a step and 95 mounted on springs 31. The board 30 is hinged to the wall 32 by means of hinges 33, and when not in use may be folded up against the wall and secured by a button, 34. A cord, 35, is fastened on the board 30, and leads to 100 and is fastened at its other end to arm 25.

In the bottom of each pocket 9 is located a block of rubber, 37, or other form of cushion for the lower end of bars 10 to strike against

when the grating 2 falls. To the upper ends of bars 10 is secured one end of coiled springs 38, their other ends being secured in the upper ends of pockets 9. Upon the grating 2 being raised the springs 38 will be compressed, and by their tension act to throw the grating with great force downward.

The operation of the invention is as follows: The arm 18 of lever 15 is raised with one hand sufficiently for the teeth 21 to clear the serrated edge 22 on the right-hand bar 10, the grating 2 is raised with the other, compressing the springs 38, and the arm 18 is then further raised to move the pin 19 into engagement with one of the holes 20, which thereby holds the grating 2 in elevated position. The board 30 is unfolded to the horizontal position, with cord 35 connected to arm 25, and the weighted ball 26 is placed on ring 24, resting on ring 23, with its cord 27 connected to arm 18 of lever 15. The cord 28 also extends from arm 25 across the lower portion of window 5 to staple 29. Upon the window 5 being raised from the outside and a burglar attempting to enter, he will bear against the cord 28 and pull arm 25 down, thereby raising the ring 24 and weighted ball 26, and causing the latter to roll down on and drop off of the inclined arm 25, thereby jerking down the arm 18 and releasing pin 19 from hole 20, which permits compressed springs 38 to throw down grating 2. The body of the burglar projecting through the window will be impaled by the sharp points 4 of grating 2, and the teeth 21, having been moved into engagement with serrated edge 22 of bar 10, the grating 2 cannot be raised, and the burglar will be held fast. As the lever 15 is located on the inside of the window, a pal on the outside cannot unfasten the grating from its lowered position. In case the burglar observes the cord 28, suspects it is connected with an alarm and cuts it, upon swinging his leg over the window-sill and pressing his foot on the step 30, which he will suppose is the floor of the room, the pressure thereon draws on cord 35, which pulls down arm 25 and causes the weighted ball 26 to be dropped, as before, and to release the grating, permitting it to be thrown down by springs 38. When the invention is not set for use, the weighted ball may be suspended by its cord 27, as well as the board 30 folded up. By this means there will be no liability of accident to a child or other innocent or careless person touching the apparatus if it were set. While the grating may drop of its own weight when released without the use of springs, the latter are preferably employed.

Having thus described my invention, what I claim as new, and desire to secure by Letters Patent, is—

1. A window-guard consisting of a metallic grating having downwardly-projecting sharp spikes on its lower edge and mounted to slide vertically inside of a window, a catch for holding the grating in elevated position and for locking it when lowered, a weighted ball

mounted on a tilting support and connected to the catch, and means adjacent to the window for releasing the catch, substantially as set forth.

2. A window-guard consisting of a metallic grating having downwardly-projecting sharp spikes on its lower edge and mounted to slide vertically inside of a window, springs bearing against the upper end of the grating to throw it downward, a catch for holding the grating in elevated position, with the springs compressed, and for locking it when lowered, a weighted ball mounted on a tilting support and having a cord connecting it to the catch, a step mounted on springs beneath the window-sill on the inside of the window, a cord leading from the tilting support and held across the lower portion of the window, and a cord leading from the tilting support and connected to the spring-step, substantially as shown and described.

3. In a window-guard, a metallic grating having sharp spikes projecting downward from its lower end and mounted to slide vertically inside of a window, a catch for holding the grating in elevated position, a detachable weight mounted on a movable support and connected by a cord to the catch to release the same, and a cord extended across the lower portion of the window and connected to the movable support, substantially as shown and described.

4. In a window-guard, a metallic grating having sharp spikes projecting downward at its lower end and mounted to slide vertically inside of a window, a catch for holding the grating in elevated position, a detachable weight mounted on a movable support, a step mounted on springs beneath the window-sill, and a cord leading from the step to the movable support, on which the weight rests, substantially as shown and described.

5. In a window-guard, the combination, with metallic grating 2, having sharp downwardly-projecting points at its lower end and vertical bars 10, with serrated edge 22, at its sides and mounted to slide vertically on window-frame 1 inside of window 2, of springs 38, connecting the upper end of grating 2 with the upper end of frame 1, lever 15, mounted in recess 17 in the window-frame 1 and having pin 19 adapted to engage holes 20 in adjacent bar 10, and a cam-shaped head, 16, with teeth 21, adapted to engage serrated edge 22 of bar 10, substantially as shown and described.

6. A window-guard consisting of the metallic grating 2, formed with the sharp points or spikes 4 at its lower end and mounted to slide in window-frame 1 on the inside of window 5, with vertical serrated bars 10, having holes 20 and located in pockets 9 in the window-frame, cushion-blocks 37, located in the lower end of pockets 9, and coiled springs 38 in their upper end connected to the window-frame and to the grating 2, a lever, 15, pivoted in a recess, 17, in the side of window-

frame 1 and having an arm, 18, projecting out of recess 17, and a cam-shaped head, 16, with teeth 21 adapted to engage serrated bar 10 and lock grating 2, and a pin, 19, adapted 5 to engage holes 20, a bracket, 23, on the side of window-frame 1, a tilting bracket, 24, hinged to bracket 23 and having an arm, 25, a weighted ball, 26, adapted to rest on brackets 24 and 23 and having a cord, 27, leading 10 to arm 18 of lever 15, a step, 30, mounted on

springs 31, a cord, 35, leading from step 30 to arm 25, and a cord, 28, leading from staple 29 across the lower portion of window 5 and attached to arm 25, substantially as shown and described.
